DESIGN FOR A GAME PIECE SET

Roy R. Hart, San Jose, Calif.

Application May 6, 1947, Serial No. 138,836

Term of patent 3½ years

(Cl. D34—5)

To all whom it may concern:

Be it known that I, Roy R. Hart, a citizen of the United States, residing at San Jose, in the county of Santa Clara and State of California, have invented a new, original, and ornamental Design for a Game Piece Set, of which the following is a specification, reference being had to the accompanying drawing, forming a part thereof.

Figure 3 is a sectional elevation of the game piece set with the individual pieces in nested relation with each other.

I claim:

The ornamental design for a game piece set, as shown.

ROY R. HART.
